UNITED STATES PATENT OFFICE.

EDWARD BAGNALL, OF PITTSBURGH, PENNSYLVANIA, ASSIGNOR TO ZOFFER PLATE GLASS MANUFACTURING COMPANY, OF PITTSBURGH, PENNSYLVANIA, A CORPORATION OF WEST VIRGINIA.

GLASS-GRINDING TABLE.

1,121,452.

Specification of Letters Patent. Patented Dec. 15, 1914.

Application filed August 7, 1914. Serial No. 855,630.

To all whom it may concern:

Be it known that I, EDWARD BAGNALL, a citizen of the United States, residing at Pittsburgh, in the county of Allegheny and 5 State of Pennsylvania, have invented certain new and useful Improvements in Glass-Grinding Tables, of which the following is a specification.

My invention relates to improvements in 10 apparatus for grinding, smoothing and polishing plate glass, and it has for its object to provide effective and economical means for cushioning and holding the glass plates upon the upper portion of the rotating table, 15 in connection with the operations performed by the usual superimposed runners.

In carrying out my invention the rotatable supporting table is provided with means for exhausting the air from its 20 interior, and a plurality of numerous supporting resilient cups, the central portions of which are in communication with such vacuum cavity, adapted to support the plate or plates and hold them by suction, or exterior air pressure, the cups being so constructed as to utilize automatically closing 25 check valve devices for preventing ingress of air through the exposed cups.

Preferred constructions of the invention 30 are shown in the accompanying drawings, in which—

Figure 1 is a plan view of the apparatus, showing certain of the exposed cups provided with inclosing valve devices. Fig. 2 is a vertical sectional view through the table, showing the glass supported upon some of the cups before air exhaustion is effected. Fig. 3 is a sectional detail view of a portion of the table, showing the plate resting on the 40 cups before the air is exhausted, one of the cups being exposed. Fig. 4 is a sectional detail view, showing the action of the glass on the cups when the air is exhausted. Fig. 5 is a view similar to Fig. 3, but showing 45 the table provided with supplemental supporting abutments. Fig. 6 is a broken plan view, showing the said construction.

The rotatable glass supporting table A is 50 preferably made of an upper wall 2 and a lower wall 3 providing an interior air cavity 4. The table is made in a plurality of sections and divided at the line 5; the sections constituting units of the complete table, connected as shown, and providing

for continuous circulation of the air throughout its entire interior, by means of the central, common rotatable air conduit or hollow spindle 6. Said spindle may be connected with the interior of the table in any suitable manner, operating as a hollow mast 60 which may act as the main stem of the table, and which may be provided with an actuating drum or pulley 7. Such drum is rigidly incorporated with the table or its central mast in any suitable manner, as 65 shown, resting upon roller or ball bearings 8, being driven by a pulley or cable engaging the peripheral groove 9, as will be readily understood.

10 represents an air exhausting device of 70 any suitable construction having an operating steam pipe connection 11, an exhaust terminal 12, and a suction conduit 13. Said conduit makes a telescoping engagement with the lower end of the rotatable mast 75 6, as indicated at 14, being provided with suitable packing or other customary or necessary attachments or parts, whereby communication may be established with the interior cavity 4 of the table at all times.

The upper wall 2 of the table, or of the several connected units comprising it, is provided with a numerous series of attaching bushings 15 tapped into the shell 2 and having a central opening, preferably tapered, 85 into which is inserted the hollow nipple 16 of the resilient cup 17. Said cup, which is preferably of rubber, is so constructed as to bear upwardly underneath the underside of the plate a, as shown in Figs. 2 and 3, and 90 to be compressed by the weight of the plate and the exterior atmospheric pressure when the air is exhausted from the interior of the table and through the hollow nipples 16, as in Fig. 4.

In utilizing the invention, the plates a, which are usually rectangular, leave uncovered certain of the cups which are thus not utilized. For the purpose of closing them against atmospheric circulation, each is provided with a check valve 18, which may be in the form of a rubber or other ball, and which will tightly seat in the upper portion of the nipple at the base of the cup, effecting the desired closure. For such purpose, and to insure seating of the valve 18 below the plane of the under side of the glass, when depressed by air pressure, the valves are

preferably seated within a supplemental containing cavity 19. This allows the valve to close the upper end of the central port 16 without interference with the plate, in cases 5 where it overlaps a portion of any cup, but does not completely cover it, thus necessitating use of the valve, as described.

Upon exhausting the air, the several cups underneath the plate or plates will be flatly 10 compressed, as indicated in Fig. 4, thereby bringing all of the several plates down to a common level, and whereby the grinding, smoothing and polishing operations of the runners may be readily accomplished.

15 If it is desired to space the cups apart, or in any case, to provide intervening supports for the glass plate, supporting abutments of any suitable kind may be extended upwardly from the main surface of the table to receive 20 the glass in its lowered position, and assist in the supporting action of the cups. Such abutments may be of any suitable construction, as shown in Figs. 5 and 6, wherein 25 transverse intersecting ribs 20 extend upwardly from the upper wall 2' of the table and between adjacent cups, throughout the area of the table. These may be of any suitable construction or arrangement, and will also assist in maintaining a uniform level of 30 the glass.

The advantages of the invention will be readily understood and appreciated by all those familiar with this class of apparatus. It obviates the necessity of the usual cementing or other laborious and expensive methods in vogue for holding the glass plates to the table, admitting of their easy and quick removal or reversal upon admission of air 35 to the interior. Such admission may be effected by any suitable valve mechanism or by operation of the pump member 10.

The number of the cups, their arrangement, shape or other features or details of construction may be variously changed or 40 modified by the skilled mechanic, but all 45

such are to be considered as within the scope of the following claims.

What I claim is:

1. A rotatable glass grinding table having a hollow interior, means for exhausting the air therefrom, and a plurality of individual suction cups of resilient material located on the upper portion of said table and having centrally arranged air suction openings communicating with the interior of the table, substantially as set forth.

2. In a glass grinding table of the class described having a vacuum cavity and an upper supporting wall, the combination with said wall of a plurality of individually inserted suction cups each having an air exhaust opening therethrough and adapted to be compressed upon the upper surface of the table, substantially as set forth.

3. In a glass grinding table of the class described having a vacuum cavity and an upper supporting wall, the combination with said wall of a plurality of individually inserted suction cups each having an air exhaust opening therethrough and provided 70 with a removable check valve device, substantially as set forth.

4. In a rotatable glass supporting table of the class described having an interior vacuum cavity and an upper supporting wall provided with upwardly projecting supporting abutments; the combination with said upper wall of a series of compressible resilient suction cups located between said abutments, having air circulation openings therethrough, and adapted to be depressed to the upper level of said abutments, substantially as set forth.

In testimony whereof I hereunto affix my signature in the presence of two witnesses. 85

EDWARD BAGNALL.
